UNITED STATES PATENT OFFICE.

HENRY B. DODGE, OF EAST SOMERVILLE, MASSACHUSETTS.

SPRING-HINGE.

SPECIFICATION forming part of Letters Patent No. 292,210, dated January 22, 1884.

Application filed October 6, 1883. (No model.)

To all whom it may concern:

Be it known that I, HENRY B. DODGE, of East Somerville, county of Middlesex, State of Massachusetts, have invented an Improvement in Hinges, of which the following description, in connection with the accompanying drawings, is a specification, like letters on the drawings representing like parts.

My invention relates to a hinge of that class in which a spring is employed, in connection with the parts of the hinge, to retain the same in definite positions with relation to one another, thus keeping the door, blind, gate, or article supported on the hinge in a definite position with relation to its frame without the use of a fastening device.

My invention consists in details of construction of the parts for holding the spring, and in the arrangement of the parts of the hinge 20 with relation to one another, as hereinafter set forth.

Figure 1 is a horizontal section of a hinge and a portion of the frame-work of a building and window-blind in connection with which 25 it is used, and Fig. 2 an elevation thereof.

The main portion or stationary member of the hinge, intended to be fastened upon the stationary frame-work A, as herein shown, upon the outside of the window-frame of a 30 building, consists of a fastening-plate, a, provided with lugs a', between which is pivoted the other member, b, of the hinge. The plate a also has supports a² a³ for the ends of the spring c, which bears laterally between its 35 ends on the movable member of the hinge. The spring-support a³ consists of a bridge connecting the lugs a', which project laterally from the hinge-pivot for this purpose. The said 40 spring-supports a² a³ also operate as stops to limit the movement of the other or movable member, b, of the hinge in either direction. The member b consists of an arm having an 45 attaching-plate, b', (shown in this instance as at right angles to the arm,) adapted to be screwed upon the rear edge of the blind, the said plate being offset toward one side of the pivot e, as shown, so that the blind or movable piece B will lie in different but parallel

planes when the blind is in the entirely closed and entirely open positions, and shown in full and dotted lines, respectively, Fig. 1. The sides of the arm b are flattened, as shown at 50 2 and 3, so that the spring c, resting against the said flattened portions, resists the rotary movement of the said arm, thus tending to hold the blind B in either position, opened or closed, without the need of any additional fastening. A considerable positive pressure upon the blind will, however, cause the spring c to yield, thus enabling the blind to be opened or 55 closed when desired. If desired, the end of the arm may also be flattened, as at 4, so that the spring c will tend to hold it in a position at right angles, or at any other desired angle, to the frame A. The spring c consists of a 60 flat plate of steel or equivalent elastic material, and the projection a² and bridge a³ are slightly recessed, so that the spring may be dropped into place before the arm b of the hinge is connected with the other member of the hinge, and the said spring will then be 65 kept in place by its own elastic force, no fastening being required to hold it.

The portion of the lugs a' that extends toward the bridge a³ is cut away on its under 70 side to pass over the usual molding surrounding the window-frame.

I claim—

A hinge composed of the stationary member, which consists of the fastening-plate a, having the lugs a' and supports a² and a³, and the spring c, supported upon the said supports a² and a³, combined with the pivoted member b, having the fastening-plate b' and plane surfaces 2, 3, and 4, to be acted upon by the 80 spring, whereby the blind, door, or other movable part is held in different positions, substantially as described.

In testimony whereof I have signed my name to this specification in the presence of two subscribing witnesses.

HENRY B. DODGE.
